UNITED STATES PATENT OFFICE.

HEINRICH OBERHOLZER, OF MÄHRISCH SCHÖNBERG, AUSTRIA-HUNGARY.

DEVICE FOR DETERMINING THE FREQUENCY OF THE SHOTS IN WOVEN FABRICS.

1,112,026.

Specification of Letters Patent. Patented Sept. 29, 1914.

Application filed June 1, 1914. Serial No. 842,123.

To all whom it may concern:

Be it known that I, HEINRICH OBERHOLZER, director, citizen of Switzerland, residing at Mährisch Schönberg, Austria-Hungary, have invented certain new and useful improvements in Devices for Determining the Frequency of the Shots in Woven Fabrics, of which the following is a specification.

10 This invention proposes an improved attachment for looms for the purpose of determining the frequency of the shots in woven fabrics, such attachment comprising special devices for operating the counter 15 warp threads, so as to bind said threads irregularly after a given number of shots and thus produce a mark. The distance between two successive marks may then be ascertained by means of a rule, which allows 20 of reading the number of shots per linear unit (centimeter, inch or the like).

In the accompanying drawing a constructional form of the present invention is exemplified.

25 In this drawing Figure 1 is a side view, Fig. 2 is a front view, Fig. 3 is a horizontal section on the line A—B in Fig. 1, Fig. 4 is a plan view of the rule.

On the shafts *c*, *d* are loosely fitted beside 30 each other two worm wheels *a*, *b* of which the wheel *a* has one tooth less than the wheel *b*. In the constructional form shown in the drawing the wheel *a* has 19 teeth, while the wheel *b* has 20 teeth. With both wheels 35 meshes a specially designed worm *e*, which, for example, may be fitted on the shaft *n* of the eccentric, and which operates to intermittently advance the two said wheels. To the wheels are secured disks *f* and *g* respectively. The disk bolted to wheel *a* has one 40 notch *h*, the disk bolted to wheel *b* two notches *i*. On these disks ride rollers *m*, *n* respectively, which are revolubly fitted on pins *o*, *p* respectively in a frame *k*, one arm 45 of which is extended and fitted on a pivot *r*. On this pivot *r* is also fitted the lever *s* to which the pull cords are connected for raising and lowering the counter threads. This lever will therefore press the rollers *m*, *n* 50 against the disks *f*, *g* respectively so that they engage in the notches *h*, *i* respectively therein, as soon as they override the same jointly; thus at 19×10 teeth, or at the 190tieth shot, or, if the ratio of the worm of

the loom is 1:2, at the 380tieth shot at a 55 distance of *v* (Fig. 4). For ascertaining the number of shots per unit, for instance one inch, a rule *t* provided with a division mark is employed, which mark is found from the formula

$$380 = v \cdot x$$

in which *v* is the distance in inches, *x* the number of shots per inch. The rule is thus divided on the basis of $\frac{380}{v}$, *v* being given in

whole figures (for facilitating the recording from 150 downward) on the scale. On the rule, furthermore, a mark *M* is provided, which is applied to a given intersecting 70 point of the line of counters. At the next intersecting point the number of shots per inch may then be read on the rule. In the constructional form shown the number of shots *x* in the distance *v* is 139. When the 75 number of shots is very large, say above 150, the space between three points is measured and the result is read on the outer scale, which is found from the formula

$$x = \frac{2,380}{v}$$

The use of a worm allows of counting 85 backward while the loom is being turned backward, in searching for shots, whereas with the apparatus hitherto disclosed this was only possible at each 4th or 8th shot, so that when the loom is turned back any further, there will be a mistake and the result 90 cannot be correct.

I claim:

A device for determining the frequency of the shots in woven fabrics, consisting of two independently revoluble worm wheels, the 95 number of teeth on said worm wheels differing by one, a notch disk attached to each worm wheel, and means co-operating with said notched disks so as to rock the lever controlling the counter warp threads when 100 the notches in said disks register.

In testimony whereof I have affixed my signature in presence of two witnesses.

HEINRICH OBERHOLZER.
